UNITED STATES PATENT OFFICE.

ROY M. PALMER, OF WASHINGTON, DISTRICT OF COLUMBIA.

AEROSTRUCTURAL BALANCE.

1,039,181.

Specification of Letters Patent. Patented Sept. 24, 1912.

Application filed June 16, 1911. Serial No. 633,468.

To all whom it may concern:

Be it known that I, ROY M. PALMER, a citizen of the United States, residing at Washington, District of Columbia, have invented certain new and useful Improvements in Aerostructural Balances, of which the following is a specification.

This invention relates to improvements in aerostructures and has particular reference 10 to an automatic balancing device.

The principal object of the invention is to provide an electrically operated means for tilting the balancing planes or ailerons.

A further object of the invention is to provide 15 means for maintaining the stability of the balancing planes or ailerons when the aerostructure is in its normal or righted position.

Another object is to provide a device of 20 this character wherein the electrically operated means is controlled by a column of mercury.

Other objects and advantages will be apparent from the following description, and 25 with particular reference to the accompanying drawings.

In the drawings: Figure 1 is an end elevation of an aeroplane equipped with my balancing device, Fig. 2 is a front elevation 30 of the same, Fig. 3 is a front elevation of the machine tilted, Fig. 4 is a diagrammatic view of the wiring of the balancing device, Fig. 5 is a diagrammatic view of a modification.

Referring to the drawings, 10 represents the framework of a biplane, 11 and 12 representing respectively the upper and lower main planes. Pivotaly mounted in the forward portion of the frame are the 40 ailerons or balancing planes 13 and 14, respectively. The ailerons may be connected in any suitable manner so as to tilt simultaneously in opposite directions, the means shown being the pulleys 15 and 16, and the 45 cords 17 and 18.

Arranged in the lower portion of the frame of the aerostructure is a bent tube 19, the angle of which points downwardly. This tube has cast into each of the arms 50 thereof the contacts 20, 21, 22, 23, on one arm, and the contacts 20', 21', 22', 23' on the other arm. The tube has a certain quantity of mercury therein, and when the tube is level, the mercury will just touch the inner 55 contacts 23 and 23', so as to keep the uppermost of the sections of the electromagnets

energized, and thus keep the ailerons steady when the aerostructure is in righted position, and according to the degree of tilt imparted by the movement of the aerostructure 60 the mercury will run over the contacts of one or the other of the arms in succession. In the lower point of the angle is cast a contact 24, the mercury always covering this contact.

Arranged near each of the ailerons is a compound electromagnet 25, composed of the separate coils 26, 27, 28, and 29, arranged one above the other and insulated from each other. The terminals of the second coil 27 70 are connected to the contact 22' and the wire 24' leading from the contact 24, so that when the aerostructure tilts in the direction to cause the mercury to touch the contact 23'; a circuit will be established by means of the 75 mercury through the contacts 22' and 24 and the source of power A, and energize the coil 27, of the magnet 25 on the opposite side of the aerostructure. These coils are of the solenoid type and have the core 30 therein. 80 The energizing of the first coil causes the core of one of the magnets to be drawn thereinto, and by means of its pivotal connection as at 31 to the aileron 13, the aileron 13 will be tilted upwardly, while the aileron 14 85 through the connections 15, 16, 17 and 18 will be tilted downwardly to present greater surface on the downward side of the aerostructure to assist in regaining its balance. The second degree of tilt of the aerostructure 90 causes the mercury to come in contact with the point 21', and thus tilt the ailerons a little farther, each successive degree of tilt moving the ailerons a little farther in opposite directions. The arrangement of 95 the magnets and the bent tube is such that when the machine as seen in Fig. 3, tilts to the right, the mercury runs into the right hand arm of the tube, and causes the connections to be made to the magnets 25, and the 100 aileron 13, it being necessary in the use of these ailerons to present the surface of the aileron on the upper side of the machine in a manner to prevent the upward movement thereof, while the aileron on the lower side of 105 the machine should be tilted to present its surface to prevent and resist downward movement. In this way the tilt of the aerostructure in one direction electrically operates the aileron on the opposite side of the 110 machine directly.

In the modification I use a series of bent

tubes of varying angles, each of which is connected to one of the coils of the electro-magnet. Thus the first degree of tilt would effect the mercury in the widest angled tube, 5 and the next degree of tilt the next smaller angle and so on. These tubes are provided with the four contacts 31, 31', 32, 32', 33, 33', 34, and 34', the contacts 31, 32, 33, and 34 controlling the tilt of the ailerons at one 10 side of the machine, while the contacts 31', 32', 33', and 34' control the ailerons on the other side of the machine, the contact 35 being the common return to the source of electricity. The contacts 31 and 31' are always in circuit, in a similar manner, and for the same reasons as stated with respect to the contacts 23 and 23'.

While I have shown particular forms of magnets and mercury tubes, I do not wish 20 to limit myself to their exact construction. The principle I wish to protect being the control of ailerons of an aerostructure by means of the contact of a column of mercury or other fluid, to complete an electric 25 circuit and energize the series of coils in succession.

While I have shown pulley and cord connections between the ailerons, I wish it to be understood that I may use any connections 30 to insure the simultaneous opposite movement thereof.

What is claimed is:

1. In an aerostructure, an automatic balancing mechanism comprising ailerons, connections therebetween, a shifting fluid column, an electrically operated means connected to the ailerons, said electrically operated means comprising a series of superimposed electromagnets, whereby upon 35 shifting of the fluid column said electrically operated means will be energized to shift the ailerons at various degrees of inclination, and means for maintaining the stability of the ailerons when said fluid column 40 returns to normal position.

2. In an aerostructure, an automatic balancing mechanism comprising ailerons, connections therebetween, a shifting fluid column, a source of electric energy, electrically 45 operated means connected to the ailerons and to the source of electric energy, said

electrically operated means comprising a series of superimposed electromagnets, a plurality of series of contact points adjacent the fluid column, whereby upon movement of said fluid column said electrically operated means will be energized at various points to shift the ailerons at various degrees of inclination, and means for energizing the electrically operated means for maintaining the stability of the ailerons when said fluid column is returned to normal position. 55

3. In an aerostructure, an automatic balancing mechanism comprising ailerons, connections therebetween, a series of superimposed electro-magnets connected to each of the ailerons, a shifting fluid column, a series of contacts adjacent the fluid column, electrical connections between the contacts and the electromagnets, means for energizing one set of said electromagnets to hold said ailerons against movement when said fluid column is normal, and means for energizing certain other of said electromagnets 75 upon the shifting of the fluid column, whereby the ailerons are actuated to various degrees of inclination. 65

4. In an aerostructure, an automatic balancing mechanism comprising ailerons, connections between the ailerons, electrically operated means arranged in succession and connected to the ailerons, a series of contacts arranged in succession, a series of electrical connections between the contacts and the electrically operated means, means actuating by tilting of the aerostructure for successively establishing a circuit in one or more of the electrically operated means, whereby to actuate the ailerons at the requisite degree of inclination, and means for establishing a circuit in said electrically operated means for maintaining said ailerons in fixed position when the aerostructure is in normal position. 80 90 95

In testimony whereof I affix my signature, in the presence of two witnesses.

ROY M. PALMER.
